Inventor:
William H. Frost,
by Arthur J. Randall,
Atty.

UNITED STATES PATENT OFFICE.

WILLIAM H. FROST, OF SAN JOSE, CALIFORNIA.

HOLDER FOR ERASERS.

Application filed October 10, 1925. Serial No. 61,817.

My invention relates to holders for erasers and the like and it has for its object to provide an inexpensive and efficient holder of this kind particularly adapted to hold a typewriter eraser. It is also an object of my invention to provide a device of this character in the form of an attachment adapted to be applied to the frame of a typewriter and to support an eraser in an accessible and convenient position out of the way of the person using the typewriter, and which will automatically return the eraser to this position after each use of the latter.

To these ends I have provided a novel holder for erasers and the like having the peculiar features of construction and mode of operation set forth in the following description, the novel features of the invention being particularly pointed out and defined in the claim at the close thereof.

In the accompanying drawings:

Figure 1 is a front elevation on a scale about twice full size of an eraser holder constructed in accordance with my invention.

Figure 2 is a central vertical sectional view of the holder shown in Figure 1.

Figure 3 is a detail hereinafter described.

My new holder for erasers, as herein shown, comprises a frame 1 made from sheet metal and constructed with a chamber 2 within which is housed a pulley 3, and also formed upon its front side with a pocket 4 within which is housed an eraser 5 of ordinary construction. The front wall of the frame 1 is formed with a hole through it which is bordered by an eyelet 6, said hole affording a passage by which chamber 2 is connected with the interior of the pocket 4 at the middle of the latter.

The pulley 3 is rotatably mounted upon a stud 7 rigidly fixed to the front wall of frame 1 and said pulley has fastened to it the outer end of a coiled spring 8 whose inner end is fastened to the post 7. A cord or chain 9 is wound onto the pulley 3 and has one end thereof fastened to the pulley while the opposite end portion extends through the eyeleted hole 6, the usual eyeleted hole 10 of the eraser 5, and through a washer 11, with the extremity thereof, outside washer 11, formed into a knot 12. It will thus be clear that with the spring 8 under tension the cord

9 will be kept wound up on the pulley 3 and the draft on the cord will serve to hold the eraser 5 within its pocket 4.

The wall of the pocket 4 is cut away, or recessed, as at 13, to leave uncovered a portion of the eraser so that said exposed portion can be grasped between the thumb and forefinger when it is desired to remove and use the eraser.

Within the pulley 3 is fixed a ring 14 whose inner periphery is formed with a pocket at opposite sides of which are shoulders 15 and 16, and with a cam surface 17 which includes about one-fourth of said inner periphery and terminates at the shoulder 15, the remaining three-fourths of said inner periphery being concentric with the axis of the pulley and terminating at the shoulder 16. Within this ring 14 are arranged three clutch balls 18 which are also housed in part within holes 19 provided in a circular plate or head 20 fixed rigidly to one end of post 7 whose opposite end, as stated above, is fixed rigidly to the frame 1. At one side thereof each hole 19 is formed with an abutment surface 21 that is approximately radially disposed and at the opposite side with a cam surface 22. The spring 8, Fig. 2, normally urges the pulley 3 and ring 20 in the direction of the arrow, Fig. 3, and normally one of the balls 18 will occupy the outer portion of the hole 19 below the axis of the pulley and the pocket formed by the shoulders 15 and 16, with the shoulder 21 opposing movement of the ball by the shoulder 16 on the pulley. Consequently when the eraser has been removed from its pocket and the cord unwound from the pulley, the spring is prevented from pulling upon or winding up the cord, by the engagement of the shoulders 16 and 21 with one of the balls. When it is desired to cause the spring to wind up the cord and return the eraser to its pocket 4, this is effected by giving a quick jerk to the cord and releasing the same whereupon the spring will wind up the cord fully and pull the eraser back into its pocket.

When the cord is jerked quickly as described, the pull upon the cord rotates the pulley clockwise a short distance during which movement the shoulder 15 shoves the ball along the cam surface 22 toward the

axis of the pulley so that it occupies a position at the inner end of its hole 19. Now, while the spring is rapidly rotating the pulley in a contra-clockwise direction and winding up the cord the pocket 15—16 is carried past the ball so rapidly that the pocket 15—16 does not occupy a position below the ball long enough to permit gravity to overcome the inertia of the ball and move it down-
5 wardly into said pocket. It will, therefore, be clear that while the clutch mechanism described automatically locks the pulley with the cord unwound therefrom while the eraser is in use, said mechanism may be caused to
10 operate automatically to rewind the cord upon the pulley and thereby return the eraser to its pocket 4, by exerting a quick jerk upon the cord. I would have it understood, however, that in some forms of my invention
15 I do not employ the clutch mechanism including the balls 18, head 20 and ring 14.

In Figure 2 I have shown the frame 1 as provided upon the rear side thereof with means for attaching said frame to the frame
20 A of a typewriter, or to any other suitable supporting fixture. This means, as shown, may consist of a clamp 22 secured by rivets to frame 1 having a jaw 23 to engage one

side of the fixture A and a clamping screw 24 to engage the opposite side thereof.

30

What I claim is:

A holder attachment for erasers comprising a sheet metal frame formed with a pulley chamber, and with a passage leading from said chamber through one wall of said frame to the exterior of the latter; a pulley rotatably mounted within said chamber; a spring for rotating said pulley in one direction; a cord wound on said pulley by said spring and having one end thereof connected with the pulley, said cord extending from said pulley through said passage; an eraser to which the outer end of said cord is connected; a cup-shaped pocket upon the front side of the frame within which said eraser is held by the cord, said cup-shaped pocket having a back wall formed with a finger notch and including an outstanding segmental wall partly surrounding the eraser so that only a relatively small and limited marginal portion of the latter is left exposed to permit the eraser to be grasped by the fingers and means on the rear side of said frame for separably fastening said frame to a support.

WILLIAM H. FROST.
